CLAIM

The ornamental design for a shopping cart, as shown and described.

DESCRIPTION

FIG. 1 is a front, right, and top perspective view of a shopping cart, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a partial enlarged view of an area labeled 8 in FIG. 1 comprising wheels; and,

FIG. 9 is another front, right, and top perspective view of the shopping cart of FIG. 1, wherein the shopping cart is in a folding state.

The broken lines framing portions of the claimed design that are illustrated for enlargements form no part of the claimed design.
